UNITED STATES PATENT OFFICE.

BENJAMIN McINNERNEY, OF COUNCIL BLUFFS, IOWA, ASSIGNOR TO WESTINGHOUSE ELECTRIC AND MANUFACTURING COMPANY, OF EAST PITTSBURGH, PENNSYLVANIA, A CORPORATION OF PENNSYLVANIA.

POLYPHASE-ELECTROMAGNET BRAKE CONTROL.

1,238,313.

Specification of Letters Patent. Patented Aug. 28, 1917.

Application filed July 18, 1914, Serial No. 851,750. Renewed April 21, 1917. Serial No. 163,706.

To all whom it may concern:

Be it known that I, BENJAMIN McINNERNEY, a citizen of the United States, residing at Council Bluffs, in the county of Pottawattamie, State of Iowa, have invented a new and useful Improvement in Polyphase-Electromagnet Brake Controls, of which the following is a specification.

My invention relates to improvements in electromagnetic means for effecting the release of dynamically actuated brakes such as are employed for retarding the motion of elevators, hoists and other machines.

One object of my invention is to provide a polyphase alternating current electromagnet which does not chatter and is free from the humming of other objectionable noises that usually characterize magnets of this type.

A second object of my invention is to provide an alternating current magnet having an armature that is positively pivoted and is firmly seated in the same position relatively to the pole pieces in successive operations.

Another object of my invention is to provide an electromagnet having an armature that is provided with a short lever arm and is of small weight in order that the movement necessary to operate the brake may be small and the resulting impact shall be substantially eliminated.

A further object of my invention is to provide an electromagnet of simplified construction which operates in connection with a mechanism that is subject to very slight wear and the efficiency of which is not decreased by such wear of its parts.

A serious disadvantage in connection with the operation of magnet brakes is the tendency for the armature to get out of adjustment because of wear of its bearing parts. In such cases, the armature does not seat properly because the plane of its face is out of alinement with the faces of the pole pieces. This condition arises in many cases from the manner in which the armature is pivoted. When the latter is pivoted near its central portion, it is obvious that a very slight wear of the bearing parts permits a relatively large lateral movement of the end portions of the armature, thus allowing the

latter to twist out of alinement with the faces of the pole pieces.

The above described construction renders it substantially impossible to secure noiseless operation for any considerable period, thereby rendering very frequent adjustments necessary to prevent undue vibrations. Another cause of chattering and vibration is the arrangement of the pole pieces in the same plane. In case one or both of the outer pole pieces becomes slightly shorter than the others, the tendency to vibrate is greatly increased, as will be readily understood.

According to my invention, the armature is pivotally mounted at its extreme end portions. The pivotal axis is arranged parallel to the plane of the faces of the coacting pole pieces and parallel to the alinement of the pole pieces. By means of this arrangement, it will be obvious that a slight wear of the bearing parts will not permit the armature to move out of alinement with the pole faces of the pole pieces. Such a condition will arise only when there is a substantial difference in the amount of wear at the respective end portions of the armature.

The electromagnet is provided with a plurality of pole pieces, the outermost of which are slightly longer than the intermediate pole pieces which are surrounded by the energizing coils. This construction insures that the armature will be seated upon parts which engage its end portions and that one of the intermediate pole pieces cannot serve as a fulcrum to produce a rocking motion. In such an arrangement, the magnetic force of the pole pieces is always exerted at a point between the pole pieces which support the armature.

The details of my invention will be described in connection with the accompanying drawings in which Figure 1 is an end view, in elevation, of a mechanism constructed in accordance with my invention, the electrical circuits being shown diagrammatically. Fig. 2 is a diagrammatic view of the polyphase electromagnet. Fig. 3 is a side view, in elevation, of the mechanism of Fig. 1, the diagram of the electrical connections being omitted.

A brake wheel *m* may be a cylindrical rotating part or drum of a machine, the mo-

tion of which is to be controlled by a brake. As illustrated, the wheel m is in the form customarily employed in connection with elevators, but it will be understood that it 5 may represent the corresponding part of any electrically controlled machine. Two brake shoes s and s' , which are pivotally mounted at the respective sides of the wheel m , are normally caused to frictionally engage the 10 periphery of the wheel by a spring x that is mounted upon an adjusting bolt y .

An electromagnet comprises a body member b having outer pole pieces e and e' and intermediate pole pieces d and d' which 15 respectively constitute core members for coils c and c' . The pole pieces e and e' are slightly longer than the pole pieces d and d' so that the plane of the faces of the former is slightly above the plane of the faces of the 20 latter. The electromagnet also comprises an armature member a which is connected, at its end portions, to levers i and i' . The levers i and i' are pivotally mounted at p and p' , and points p and p' are so arranged 25 that the pivotal axis of the armature is parallel to the plane of the faces of the pole pieces e and e' . When the coils are energized, the armature is seated upon the faces 30 of the pole pieces e and e' .

One end of the armature member a is connected to the brake shoe s by the lever i , a link j , a bell-crank lever k and an eye bolt l . The other end of the armature is connected 35 to the brake shoe s' by a similar mechanism i' , j' , k' and l' . The pivotal axis of the armature a through the points p and p' is so arranged that the shortest possible movement of the armature operates through the lever mechanism above described to effect 40 the disengagement of the brake shoes. The eye bolts l and l' are provided with adjusting nuts for varying the positions of the brake shoes relatively to the armature.

As indicated diagrammatically in Fig. 1, 45 the coils c and c' are supplied with current from a three-phase source. The coil c is connected to line conductors 1 and 2 by conductors 10 and 20, respectively. The coil c' is similarly connected to line conductors 2 50 and 3 by conductors 21 and 30, respectively. While this system of connections is shown by way of example, it is the preferred manner in which current is supplied for energizing the coils c and c' . It is well known 55 that the total power delivered to such a circuit is always greater than zero and that at least one of the coils c and c' is always energized to some degree. It will be evident, therefore, that a pull will be exerted on the 60 armature member a by one or both of the pole pieces e and e' as long as the coils are in circuit. A pull will also be exerted substantially continuously by each of the pole pieces d and d' .

65 The important advantage of such an ar-

angement lies in the fact that a constant pull is exerted on the armature between its points of support and there is no period in which the armature is loosely held against either of the pole pieces. This feature, together with the manner of pivotally mounting the armature so as to prevent any twisting motion, insures that the armature will always be firmly seated upon the coacting pole pieces. 75

The operation of the mechanism will be readily understood. When the line conductors 1, 2 and 3 are connected to any suitable source, (not shown), the coils c and c' will be energized and the armature a will be 80 drawn downwardly by the magnetic force of the poles d and d' and e and e' . Since the plane of the armature is parallel to that of the faces of the pole pieces e and e' , the armature will be firmly seated upon the pole 85 pieces and retained in that position while the coils are energized. The downward movement of the armature a operates through the lever mechanisms to separate the brake shoes s and s' against the force of 90 the spring x and thereby release the wheel m .

When the magnet is deenergized by opening the circuits of the coils c and c' , the spring x operates to effect the engagement of the brake shoes s and s' with the wheel m 95 and thus bring the motor or other machine with which it may be connected quickly and safely to rest.

An arrangement in which the coils c and c' are connected to a two-phase source is 100 shown diagrammatically in Fig. 2. The coil c is connected to line conductors 1 and 2 by means of conductors 10 and 20, respectively, and the coil c' is similarly connected to line conductors 3 and 4 by means 105 of conductors 30 and 40, respectively. It is understood, however, that the arrangements of the circuits for the coils c and c' are shown by way of example only and that I do not wish to limit myself to either of 110 the arrangements shown and described.

The advantages of my invention will be apparent to those skilled in the art to which my invention appertains. The mechanism is composed of few and simple parts. The 115 armature is positively pivoted in such a manner that a slight wear of the bearing parts cannot affect its quiet operation. A convenient means is provided for making such adjustments as may be necessary in 120 order that the several moving parts may have their proper relation. The magnet operates through a very short distance to effect the engagement and disengagement of the brake shoes and maintains its operative 125 position substantially without noise and without chattering.

What I claim and desire to secure by Letters Patent is:

1. In a brake, the combination with a 130

- brake shoe, of a magnet having a plurality of pole pieces, the outermost of which are longer than the others, and a movable armature connected to said brake shoe for coacting with said outermost pole pieces.
2. In a brake, the combination with an armature which is pivotally supported at its end portions, and a pair of brake shoes respectively connected to said end portions, of means for exerting a substantially constant pull upon said armature between its points of support.
3. In a brake, the combination with a pair of brake shoes, of a magnet having a plurality of pole pieces, an armature pivotally supported at its ends and adapted to seat upon at least two of said pole pieces, and means for adjustably connecting each end of said armature to one of said brake shoes.
4. In a brake, the combination with a brake shoe, of a magnet having a plurality of aligned pole pieces, the outermost of which project beyond the plane of the others, and an armature connected to said brake shoe and having a pivotal axis substantially parallel to the plane of the faces of the outermost pole pieces.
5. In a brake, the combination with a brake shoe, of a magnet having a plurality of aligned pole pieces, the outermost of which project beyond the plane of the others, and an armature connected to said brake shoe and having a pivotal axis substantially par-

allel to the alignment of said pole pieces, said armature being adapted to seat upon the outermost pole pieces.

6. In a brake, the combination with a brake shoe, of a magnet having a plurality of aligned pole pieces, the outermost of which project beyond the plane of the faces of the others, coils upon intermediate pole pieces, and a pivotally mounted armature connected to said brake shoe for coacting with the outermost pole pieces.

7. In a brake, the combination with a brake shoe, of a magnet having a plurality of aligned pole pieces, the outermost of which project beyond the plane of the faces of the others, coils upon intermediate pole pieces, and an armature connected to said brake shoe having a pivotal axis substantially parallel to the alignment of said pole pieces and adapted to seat upon the outermost pole pieces.

8. In a brake, the combination with an armature which is pivotally supported at its end portions, and a pair of brake members connected to said armature and aligned with the axis of pivotal support, of means for exerting a substantially constant pull upon said armature between its points of support.

BENJAMIN McINNERNEY.
